UNITED STATES PATENT OFFICE

KENNETH M. SIMPSON, OF NEW YORK, N. Y.

CARBONIZING PROCESS

Application filed February 15, 1932. Serial No. 593,137.

This invention relates to a process for distilling or carbonizing coals and like carbonizable materials. While the invention is particularly applicable to the low temperature carbonization or distillation of coals, it is also capable of use for high temperature work to manufacture by-product coke, etc.

It is an object of the invention to provide a process in which coal can be carbonized in a minimum time and also permit the carbonization of large amounts of coal in unit installations. It is well known that coal must be carbonized in relatively narrow thicknesses in order to prevent loss of time in the carbonization operation, but efforts to treat coal in this way have heretofore been confined to methods which permitted only a small unit capacity or output.

It is also an object of the invention to make as good coke as is possible at the temperatures employed. By use of the process herein described, coke can be produced that will be dense, hard and tough and will in both size and quality be a satisfactory fuel. It will thus be seen that the objects of the invention are to provide a process whereby coal can be carbonized in a minimum time and that large capacity per unit of equipment can be obtained and that the coke produced shall have the qualities generally understood as distinguishing good coke. In connection with this last point it should be noted that many of the methods that have been tried for the carbonization of coal at low temperatures have produced in some cases a pulverulent char and in other cases a granular mass of spherical aggregates. Material such as that can be used as a domestic fuel only after briquetting, which is an expensive operation. Also, no briquet so far produced has the fuel characteristics of first class domestic coke.

With the foregoing conception in mind, the invention primarily comprises a process in which the coal undergoing treatment has a most substantial area exposed to the heating action of the gases whereby in a short time the heat, which may be of a low temperature, will penetrate the coal and cause a rapid carbonization thereof.

More specifically, my invention embodies a

process in which a number of parallel coal charges are moved through a carbonizing retort on a movable support, and which support is so constructed as to permit the heating gases to play on both sides of each charge, thereby rapidly penetrating the charge.

As a further feature of my invention, vapors and gases evolved from the coal during the carbonization thereof, are burned in the retort and the resultant products of combustion employed as the heating gases for the parallel coal charges moving through the retort.

In Figure 1 of the drawing, I have shown diagrammatically a retort which may be of any well known construction, and in Figure 2 I have shown a view of one of the carrying units for supporting the coal charges that are moved through the retort.

Referring now more particularly to the drawing wherein like reference characters indicate corresponding parts, the numeral 1 designates a retort through which suitable trucks 2 are adapted to be moved continuously or intermittently. At one end, this retort has a door 3 and at its opposite end a door 4. The retort is heated, in a manner hereinafter described, so that a temperature of approximately 600° C. is maintained therein if the apparatus is being used for the low temperature carbonization of coal. Obviously, if the apparatus is being used for the production of by-product coke, high temperatures will be employed, the necessary temperatures being well known to those skilled in the art. From the retort, vapor and gas discharge lines 5 lead to any suitable form of condenser for the recovery of the condensable products and the separation of such products from the uncondensable gases which may be consumed as desired.

Referring now to Figure 2, it will be understood that the reference character 6 merely represents one of the several carrying units that move through the retort. These units may be drawn through the retort by an endless driving belt 6' driven by suitable power mechanism, and which cooperates therewith and progressively advances the units through the retort. Any number of the units may be

employed and they may be connected together if desirable. Each unit has a bottom 7 and supporting wheels 8. Each unit or truck is provided with a series of spaced vertically 5 extending partitions 9, preferably made of cast iron, and of about one inch in thickness. These plates are spaced about four inches apart. It will be understood, however, that the plates can be of greater distance apart if 10 desirable, the specific degrees herein given being merely set forth as an illustration of one successful arrangement of these plates, particularly for low temperature work.

In applying coal to each unit or car, I only 15 fill alternate compartments formed by the partition plates 9. For instance, the compartments that are filled are designed by the reference characters 10, 11, 12, 13 and 14. This means that adjacent each filled com- 20 partment there is an empty compartment, the empty compartments being designated by the characters 15, 16, 17 and 18. I have dis- covered that, when filling the alternate com- 25 partments only, a sufficient area is provided for each charge to be exposed to a maximum quantity of heating gases. The gases play 30 freely through the unfilled compartments and the walls of these compartments, being of relatively thin cast iron, freely conduct the heat of the gases to the filled compartments. It is therefore apparent that large areas of 35 the fuel charges are exposed at one time to the action of the heating gases. I find that this results in a very rapid low temperature carbonization of the charges, and that when using a temperature of 600° C., it will not take more than four hours to carbonize the charges contained on each truck.

Should the process be used for the produc- 40 tion of by-product coke, then the operation will be the same, except that in the heating retort, I will preferably maintain a temperature of about 900° C. The movement of the units or carriers through the retort in either 45 instance is so governed that before any unit emerges from the retort it has been therein a sufficient period of time to effect the desired carbonization of the coal charges therein. When the charge has been carbonized, it is 50 removed from the unit or carrier and the compartments again filled with fresh coal or sim- ilar material.

The retort having been brought to an initial distillation temperature by the introduction 55 of heating gases from an extraneous source, the heating gases for continuance of the carbonizing operation are thereafter generated within the retort by burning the evolved va- 60 poros and gases, or a sufficient portion thereof to maintain the requisite temperatures, in the retort. For this purpose, the retort is pro- 65 vided, preferably near its upper portion, with longitudinally spaced air inlet pipes 19 whereby controlled quantities of air may be 70 commingled with the vapors and gases 75 80 85 90 95 100 105 110 115 120 125 130

evolved from the coal to induce combustion of the volatilized hydrocarbons. The resultant combustion products, constituting the heating gases, play freely through the empty compartments or passages 15 to 18, and rapidly and effectively heat the coal charges as already described. The amount of air introduced will, of course, be governed by the quantity of vapors and gases which must be burned to maintain the requisite temperature in the retort, and it will be understood that in high temperature carbonization, more air will be introduced, and hence more vapors and gases burned, than in a low temperature carbonizing operation.

Having thus described the invention, what I claim is:

1. A process for carbonizing coal which comprises arranging the coal in a plurality of spaced relatively thin parallel charges, introducing the charges to an elongated carbonizing zone, initially heating the carbonizing zone to a distillation temperature to evolve vapors and gases from the coal, introducing a controlled amount of air to the carbonizing zone to burn a sufficient amount of the evolved vapors and gases to maintain a temperature of at least 600° C. in the carbonizing zone without burning any appreciable quantity of the coal, advancing the charges in unison through the carbonizing zone and coking the same therein by the heat of said burning, and then removing the carbonized charges from the carbonizing zone.

2. The process as defined by claim 1, fur- 100 ther characterized in that the air is intro- duced to the carbonizing zone at spaced points in the path of travel of the charges there- through.

In testimony whereof I affix my signature.

KENNETH M. SIMPSON.
